SPECTACLE NASAL CLAMP

Robert H. Ramp, Pittsford, N.Y., assignor to Bausch & Lomb Incorporated, Rochester, N.Y., a corporation of New York

Filed June 28, 1967, Ser. No. 7,629

Term of patent 14 years

(Cl. D57—1)

FIG. 1 is a front elevational view of a spectacle nasal clamp embodying my new design;

FIG. 2 is a rear elevational view thereof;

FIG. 3 is a top plan view thereof;

FIG. 4 is a side elevational view thereof; and

FIG. 5 is a side elevational view of another embodiment of the design shown in FIGURES 1-4.

The partial broken line showing of the wearer and spectacle frame in FIGS. 4 and 5 is for illustrative purposes only.

I claim:

The ornamental design for a spectacle nasal clamp, substantially as shown and described.
